CAM LAPPING MACHINE

Herbert S. Indge, Westboro, Mass., assignor to
 Norton Company, Worcester, Mass., a corpora-
 tion of Massachusetts

Application January 27, 1945, Serial No. 574,847

7 Claims. (Cl. 51—154)

1

This invention relates to grinding machines, and more particularly to a cam lapping machine.

One object of the invention is to provide a simple and thoroughly practical lapping machine for lapping a cam to a predetermined finish and contour. Another object of the invention is to provide a cam lapping machine with an automatically actuated abrasive paper feed which continuously presents a fresh abrading surface during the lapping operation. A further object of the invention is to provide a cam lapping machine in which the lapping arm is controlled by a master cam positioned in axial alignment with and rotatable with the cam to be lapped so as to eliminate the necessity of providing a synchronous driving mechanism between the master cam and the cam to be lapped.

Another object of the invention is to provide a cam lapping machine having a pivotally mounted cam lapping arm the movement of which is controlled by a master cam mounted on the arbor supporting the cam to be lapped. A further object of the invention is to provide a cam lapping machine with a pivotally mounted cam lapping arm, the movement of which is controlled by a pivotally mounted arm carrying a follower which engages a master cam mounted on the same arbor with the cam to be lapped. A further object of the invention is to provide a manually operable toggle operated mechanism to move the cam lapping arm and the follower supporting arm to and from an operative position. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings in which is shown one of various possible embodiments of the mechanical features of this invention,

Fig. 1 is a front elevation of the improved cam lapping machine;

Fig. 2 is a fragmentary diagrammatic perspective view of the cam lapping machine;

Fig. 3 is a fragmentary side elevation, on an enlarged scale, showing the cam lapping arm and the abrasive paper feed mechanism; and

Fig. 4 is a fragmentary side elevation, on an enlarged scale, of the operating end of the cam lapping arm.

A lapping machine has been illustrated in the drawings comprising a base 10 which serves as a support for a longitudinally reciprocable work

supporting table 11. In order to facilitate a free and easy reciprocatory movement of the table, it is preferably supported on an anti-friction slide-way comprising a pair of rows of spaced anti-friction balls 12 and 13 (Fig. 3).

The table 11 is preferably arranged so that it may be reciprocated during the lapping operation to produce a break-up motion between the work to be lapped and the lapping element. An electric motor 14 is mounted on a bracket 15 which is fixed to the base of the machine. The motor 14 is provided with a driving pulley 16 which is connected by a V-belt 17 with a pulley 18 mounted on the drive shaft of a speed reduction unit 19. The speed reduction unit 19 is provided at its upper end with a positively driven eccentrically positioned stud (not shown) which is operatively connected to the left-hand end of a connecting rod 20. The other end of the connecting rod 20 is pivotally connected by a stud 21 with the left-hand end of the work table 11. It will be readily apparent from the foregoing disclosure that when the motor 14 is set in motion, a revolving motion will be transmitted through the reduction gear unit 19 to the eccentric stud (not shown) to reciprocate the connecting rod 20 and the table 11.

The table 11 serves as a rotatable support for a work arbor 21 comprising a headstock 22 and a footstock 23 which are provided with work supporting centers 24 and 25, respectively. A driving mechanism is provided for rotating the work arbor 21 during a lapping operation comprising an electric motor 26 which is supported on a bracket 27 fixed relative to the base 10 of the machine. The motor 26 is provided with an armature shaft 28 which serves as a support for a multi-V-groove pulley 29. The pulley 29 is connected by a V-belt 30 with a V-groove pulley 31 mounted on the left-hand end of the headstock spindle (not shown).

The work supporting arbor 21 serves as a support for a master cam 35 and a cam to be lapped 36. The arbor 21 is preferably formed so that the cam to be lapped may be positioned thereon for a lapping operation to locate it in predetermined timed relation to the master cam 35. In order to lap the cam 36 to the desired and predetermined finish and contour, a pivotally mounted lapping element is provided comprising a lapping arm 38 which is pivotally mounted on a shaft 39 which is supported by a bracket 40 which is fixed relative to the base 10 of the machine. The lapping arm 38 is normally urged into operative engagement with the cam 36 to be lapped by means of a tension spring 41 the upper end of which is connected to a stud 42 on the arm 38 (Fig. 3) and

the lower end of which is fastened to the bracket 40. In order yieldably to support a lapping element, a resilient supporting shoe is preferably provided which in the present instance comprises an endless leather belt 43 which is passed around a pair of collars 44 and 45. The collars 44 and 45 are supported by studs 46 and 47, respectively, which are carried by the lapping arm 38. The stud 46 is provided with an eccentric portion for supporting the roller 44 so that the roller 44 may be adjusted relative to the roller 45 to facilitate tensioning the belt 43 as desired.

It is desirable to provide a flexible abrading or lapping element, preferably comprising a continuous strip of abrasive paper which may be continuously fed during the lapping operation so as at all times to present a fresh abrading surface to lap the face of the cam. A reel of abrasive paper 48 is mounted on the upper end of an arm 49. The abrasive paper 50 passes from the reel 48 around the nose of the lapping arm formed by the belt 43 and passes backwardly between a pair of pinch rolls or gears 51 and 52, respectively. The gears or pinch rolls 51 and 52 are rotatably supported by studs 53 and 54, respectively, the ends of which are supported in brackets 46 and 40a which project upwardly from the base 10 of the machine.

A motor driven mechanism is provided for continuously rotating the pinch rolls 51 and 52 at a slow uniform rate during the entire lapping operation. This mechanism comprises an electric motor 55 having an integrally mounted gear reduction unit 56 formed integrally therewith. This motor 55 and speed reduction unit 56 may be any of the standard and well known units in common use today such as, for example, the Bodine reducer motor. This reducer motor unit 50-51 is fixedly supported on the bracket 40a and serves positively to drive the pinch roll or gear 51 so as continuously to draw the abrasive paper from the reel 48 over the nose of the lapping arm 38 and pass the worn abrasive paper 50 toward the rear of the machine. It will be readily apparent from the foregoing disclosure that a fresh abrading surface is continuously being provided during the entire lapping operation.

In order to control the swinging movement of the pivotally mounted lapping arm 38, a pivotally mounted follower arm 60 is pivotally mounted on the shaft 39 and spaced from the lapping arm 38. The forward end of the follower arm 60 is provided with a follower roller 61 which is arranged to engage the master cam 35 during a lapping operation. The follower roller 60 is preferably of a diameter equal to the abrasive covered nose of the lapping arm 38.

In order that the master cam 35 and follower arm 60 may control the swinging movement of the lapping arm 38, the lapping arm 38 is provided with a stud 62 which is fixed relative to the lapping arm 38. The stud 62 passes through an elongated aperture 63 (Fig. 3) formed in the follower arm 60. A stop screw 64 is provided on the follower arm 60 to locate the stud 62 relative to the follower arm 60. In order to provide a yieldable connection therebetween, a compression spring 65 is contained within an aperture 66 formed in the follower arm 60. The lower end of the compression spring 65 engages the stud 62 and the upper end thereof is engaged by a screw 67 by means of which the tension of the spring 65 may be varied as desired. It will be readily apparent from the foregoing disclosure that by adjusting the screw 64, the position of the fol-

lower roller 61 relative to the nose of the lapping arm 38 may be readily adjusted as desired and that the provision of the spring 65 provides a yieldable connection between the lapping arm and the follower roll supporting arm 60.

It is desirable to provide a suitable mechanism for swinging the lapping arm together with the follower arm 60 to and from an operative position. This mechanism may comprise a manually operable lever 70 which is pivotally mounted on the stud 71. A toggle lever 72 is also mounted on the stud 71 and is fixedly supported thereon so that the lever 70 and the toggle lever 72 form a bell crank lever. The lower end of the toggle lever 72 is connected by a stud 73 with a toggle lever 74 which is pivotally mounted on a stud 75 which is fixedly supported on the bracket 40. A pivotal support is provided for the stud 71 comprising a pivotally mounted link 76, the left-hand end of which is mounted on a stud 77 carried by the bracket 40.

In the full line position of the parts as shown in Fig. 3, that is, with the lever 70 in a downward or horizontal position, the lapping arm 38 and the follower arm 60 are in operative positions with the abrasive paper 50 engaging the cam 36 to be lapped and the follower roller 61 engaging the master cam 35. After the lapping operation has been completed, the lever 70 may be moved in a counterclockwise direction into the dotted line position 70a (Fig. 3) so that the toggle levers 72 and 74 assume positions 72a and 74a (Fig. 3), thus serving to raise the follower arm 60 and the lapping arm 38 out of engagement with the master cam 35 and the cam 36.

The operation of this improved cam lapping machine will be readily apparent from the foregoing disclosure. A cam 36 to be lapped is mounted in position on the arbor 21. The arbor 21 supporting the master cam 35 and the cam to be lapped 36 is then mounted in position, being rotatably supported by the headstock center 24 and the footstock center 25. After the work has been thus positioned, the motor 14 is set in motion to cause a reciprocatory motion of the table 11, the electric motor 26 is set in motion to rotate the work arbor 21, and the motor 50 is started to provide a continuous feeding movement of the strip of abrasive lapping paper 50. The control lever 70 may then be swung from the dotted line position 70a into the full line position 70 (Fig. 3) so as to shift the toggle levers 72 and 74, thus allowing the lapping arm 38 and the follower arm 60 to swing downwardly under the tension of the spring 41 until the master cam roller 61 engages the master cam 35 and the abrasive paper 50 engages the cam 36 to be lapped. The lapping operation may be continued for the desired time interval, that is, until the surface of the cam being lapped has been lapped to the desired finish and contour during which time the abrasive paper 50 is advanced continuously during the entire lapping operation. After the lapping operation has been completed, the lever 70 may again be swung into dotted line position 70a to raise the lapping arm 38 and the follower arm 60 to inoperative positions so that the abrasive paper 50 and the follower roller 61 are out of engagement with the cam 36 and the master cam 35, respectively.

It will thus be seen that there has been provided by this invention apparatus in which the various objects hereinabove set forth together with many thoroughly practical advantages are successfully achieved. As many possible embodi-

ments may be made of the above invention and as many changes might be made in the embodiment above set forth, it is to be understood that all matter hereinbefore set forth or shown in the accompanying drawings is to be interpreted as illustrative and not in a limiting sense.

I claim:

1. In a cam lapping machine having a base, a rotatable work support including a headstock and a footstock, a work supporting arbor for supporting a cam to be lapped, a movably mounted cam lapping arm on said base having a nose piece, a flexible abrasive lapping element on said arm surrounding said nose piece, a master cam on said arbor adjacent to the cam to be lapped, a movably mounted arm having a rotatable follower roller in engagement with said master cam, yieldable means to maintain said follower roller in engagement with said master cam, interconnections between said cam lapping arm and said follower whereby said follower roller imparts a controlled movement to said lapping arm and element, and manually operable means simultaneously to move said lapping arm and said follower arm to and from an operative position.

2. In a cam lapping machine having a base, a rotatable work support including a headstock and a footstock, a work supporting arbor for supporting a cam to be lapped, a pivotally mounted cam lapping arm on said base having a semi-cylindrical nose piece, a flexible abrasive lapping element on said arm surrounding said nose piece, a master cam on said arbor adjacent to the cam to be lapped, a pivotally mounted arm having a rotatable follower roller in engagement with said master cam, yieldable means to maintain said follower roller in engagement with said master cam, interconnections between said cam lapping arm and said follower whereby said follower roller imparts a controlled swinging movement to said lapping arm and element, and means including a manually operable lever simultaneously to swing said lapping arm and said follower arm to and from an operative position.

3. In a cam lapping machine having a base, a rotatable work support including a headstock and a footstock, a work arbor supported thereby to support a cam to be lapped, a pivotally mounted cam lapping arm on said base having a nose piece, a flexible abrasive lapping element on said arm which wraps around said nose piece, a master cam on said arbor adjacent to the cam to be lapped, a pivotally mounted arm having a rotatable follower roller in engagement with said master cam, yieldable means to maintain said follower roller in operative engagement with said master cam, adjustable connections between said follower arm and said cam lapping arm whereby

said lapping element may be adjusted relative to said master cam follower roller, and manually operable means simultaneously to swing said lapping arm and said follower arm to and from an operative position.

4. In a cam lapping machine having a base, a rotatable work support including a headstock and a footstock, a work arbor supported thereby for supporting a cam to be lapped, a pivotally mounted cam lapping arm on said base, a lapping element on said arm, a master cam on said arbor adjacent to the cam to be lapped, a pivotally mounted arm having a rotatable follower roller in engagement with said master cam, yieldable means to maintain said master cam roller in operative engagement with said master cam, adjustable connections between said follower arm and said cam lapping arm whereby the lapping element may be adjusted relative to the master cam follower roller, and means including a manually operable toggle lever mechanism to move said follower arm and said lapping arm to and from an operative position.

5. In a cam lapping machine as claimed in claim 1, the combination with the parts and features therein specified, of a lapping element comprising a continuous strip of flexible abrasive, a reel to support said abrasive, said flexible abrasive wrapping around the end of said lapping arm, a pair of opposed feed rollers engaging opposite sides of said flexible abrasive element, and means including an electric motor continuously to rotate at least one of said feed rollers so as to impart a slow continuous feeding movement to said flexible abrasive element during a lapping operation.

6. In a cam lapping machine as claimed in claim 1, the combination with the parts and features therein specified, of a lapping arm having a nose piece comprising an endless flexible tape, a pair of rollers on said lapping arm to support said tape, a flexible abrasive element surrounding said nose piece, and means to adjust one of said rollers relative to the other roller to tension said tape, said tape serving as a support for the flexible abrasive element.

7. In a cam lapping machine as claimed in claim 1, the combination with the parts and features therein specified, of a lapping arm having a nose piece comprising a pair of spaced rollers, one of said rollers being mounted adjacent to the end of said lapping arm, an endless flexible tape surrounding said rollers, one of said rollers being adjustable relative to the other to tension the tape as desired, and the diameter of the roller on the end of said arm plus the thickness of the tape and abrasive element being equal to the diameter of said follower roller.

HERBERT S. INDGE.
